UNITED STATES PATENT OFFICE.

LINDSLEY SCHEPMOES, OF HASBROUCK HEIGHTS, NEW JERSEY, ASSIGNOR TO THE SAFETY CAR HEATING & LIGHTING COMPANY, A CORPORATION OF NEW JERSEY.

DESIGN FOR A LAMP.

41,591.

Specification for Design.

Patented July 18, 1911.

Application filed April 14, 1911. Serial No. 621,170. Term of patent 7 years.

To all whom it may concern:

Be it known that I, LINDSLEY SCHEPMOES, a citizen of the United States, residing in Hasbrouck Heights, county of Bergen, and State of New Jersey, have invented a new, original, and ornamental Design for Lamps, of which the following is a specification, reference being had to the accompanying drawing, forming a part thereof.

The figure is an elevation of a lamp showing my new design.

I claim—

The ornamental design for a lamp as shown.

LINDSLEY SCHEPMOES.
